UNITED STATES PATENT OFFICE.

LOUISE K. LINDLEY, OF CHARLEVOIX, MICHIGAN.

INFANT'S GARMENT.

Application filed January 28, 1926. Serial No. 24,366.

The invention relates to a novel form of garment for newborn and relatively young children and has for its object to provide a garment so formed as to be spread flat, the infant placed thereon and the several portions of the garment folded and wrapped about the torso, including the abdomen and the arms, in such manner as to constitute a relatively snug fitting abdominal bandage, but without interfering with the normal action of the heart and lungs. To this end, the invention comprises a garment, preferably formed with two sections of cloth united in the middle section of the back to form a double thickness over the spinal region, two free flaps adapted to be overlapped to form the front of the garment, a neck opening intermediate the front and back portions, which opening is completed by the closing of the front forming flaps, foldable sleeve forming sections extending substantially normal to the intermediate section of the body portion, and lateral flaps extending from the lower portion of the back, each flap having a curved upper edge merging into the back adjacent to the sleeve forming sections, said flaps being adapted to be folded in lapped relation over the abdomen alone to form, with the lower portion of the back, an abdominal bandage.

The invention is illustrated in the accompanying drawings, in which:

Fig. 1 is a view of an infant wearing the garment.

Fig. 2 is a plan view of the complete garment in spread relation to receive the infant.

Referring to the drawings, the body portion proper of the garment comprises a back section, including members 1, 1, which are overlapped and united by stitching 4, 4 longitudinally of the center of the back, so as to overlie the spinal region from the neck down, and a front section comprising two free flaps 2, 2, which are of substantially the same length as the back section and are adapted to be lapped over the front of the body from the neck downward. Intermediate the front and back sections and in substantially the center of the fashioned garment, when in spread relation, is a neck opening 5, which is closed when the front flaps are brought into overlapping relation.

Extending from the mid portion of the body portion are two sleeve forming sections 6, the lower edge of each section being

gathered at an intermediate portion to form an elbow receiving fullness 7.

Each of the back forming sections 1, 1 is provided with a lateral extension or flap 8, the lower marginal edge of which is an extension of the bottom 11 of the back and the upper edge is cut on a curve as at 9, so that the upper edge of each flap 8 gradually merges into the back at or about the junction of the sleeve forming sections with the body portion. Ordinarily, the flaps or extensions 8 will extend laterally from the back of the garment approximately the same distance as the sleeves, but, if desired, these flaps may be made considerably longer. The edges of the fashioned garment are preferably bound with tape or the like, as indicated at 11, to which is secured suitable fastening devices, such as the usual form of snap fasteners 12, which are applied to the edges of the sleeve forming sections and the neck enveloping edges.

In applying the garment to a new-born infant, or small child, the garment is spread out flat and the infant laid thereon on its back. The front forming flaps 2, 2 are then folded over the front portion of the body and the neck opening closed by the fastening devices; the sleeve forming sections 6, 6 are wrapped about the arms and the edges connected by the snap fasteners 12, after which the lateral flaps 8, forming extensions of the lower portion of the back, are folded successively over the abdomen, and the upper section secured to the lower section by suitable pins, or the like, so that said lateral flaps 8 and the lower portion of the back constitute an abdominal bandage, which envelopes the abdomen alone and holds the garment in its properly adjusted position to resist any tendency to work upward. The curved upper edges of the flaps 8, when the flaps are wrapped relatively tight over the abdomen, tend to support the back of the infant and assist in maintaining the garment in its properly adjusted position. These flaps, when in folded relation, however, exercise no pressure upon the chest of the infant, so that the garment does not interfere, in any way, with the free action of the heart and lungs, but, on the other hand, the flaps, when operating with the lower portion of the back as an abdominal band, may be drawn tight enough to serve the usual and necessary functions of the abdominal

band, which is generally applied as a separate element. It will be seen, therefore, that the garment includes the equivalent of the usual shirt enveloping the entire torso and the arms, together with an integral abdominal band formed in part by the lower portion of the back and in part by the lateral flaps, which latter may be folded over the abdomen with the necessary degree of pressure to prevent protrusions, ruptures and the like, but which abdominal band will not, in any way, interfere with the normal action of the heart and lungs. It will also be noted that the garment may be quickly applied and removed from the infant by a series of simple folding and unfolding operations, so that exposure of the infant may be reduced to a minimum.

What I claim is:

1. An infant's garment comprising a back portion, a front portion including free overlapping flaps, with a neck opening intermediate the front and back, foldable sleeve forming sections extending substantially normal to the front and back, and lateral

flaps extending from the lower portion of the back each having an upper edge curving upwardly throughout substantially its entire extent and merging into the back adjacent the sleeve forming sections, the lower portion of said back portion and said flaps co-operating to form an abdominal band.

2. An infant's garment comprising a body portion fashioned from two blanks including overlapping sewed sections forming a double thickness over the spinal region of the back, centrally overlapping free flaps constituting the front, foldable sleeve forming sections extending laterally from the intermediate portions of the blanks, a centrally disposed neck opening, and lateral flaps extending from the lower portion of the back each having an upper edge curving upwardly throughout substantially its entire extent and merging into the back adjacent the sleeve forming sections, the lower portion of said back portion and said flaps co-operating to form an abdominal band.

In testimony whereof I affix my signature.
LOUISE K. LINDLEY.
